UNITED STATES PATENT OFFICE.

SAMUEL CRUMP, OF NEW YORK, N. Y., ASSIGNOR TO THE CRUMP COMPANY, OF NEW YORK, N. Y., A CORPORATION OF NEW YORK.

APPARATUS FOR CLEANING PRINTERS' ROLLERS.

1,058,040.

Specification of Letters Patent.

Patented Apr. 8, 1913.

Application filed June 22, 1912. Serial No. 705,189.

To all whom it may concern:

Be it known that I, SAMUEL CRUMP, a citizen of the United States, and a resident of New York city, in the county of New York and State of New York, have invented certain new and useful Improvements in Apparatus for Cleaning Printers' Rollers, of which the following is a specification.

The invention relates to improvements in apparatus for cleaning printers' rollers, and by preference I embody my invention in a printing press as an attachment thereto so as to enable the effectual automatic cleaning or washing of the ink distributing and form 15 rollers, as well as the form itself when desired, while the same are on the press and driven by the press operating means.

My invention is based on the conception of cleaning all of a train of rollers of a press 20 while they are on the press and whether they be many or few, simultaneously, quickly, effectually and with the least possible added expense to the cost of manufacturing the press.

The operation or method of utilizing my 25 invention is based on the principle of transferring the color or ink from one roller to another in series through the train of rollers to a final draw-off roller, preferably of 30 printer's roller composition, from which the color is removed by a scraper held against the same. The roller to which the scraper is applied being constantly deprived of ink, will become the point of delivery for the ink 35 from all the other rollers in the train, and gradually and in an almost incredibly short time all the ink on the rollers will transfer to said final roller and be removed, all of the rollers on the press becoming thor- 40oughly cleansed and also dried of the kerosene or other solvent which I will pour on the rollers during the cleansing operation for softening the ink. When the form rollers are left in contact with the form during 45 the cleansing operation, the latter, then being a part of the train of transfer surfaces, will also become effectually cleaned, the ink therefrom transferring to the rollers which are constantly drawn from by the roller to 50 which the scraper is applied.

My invention pertains more particularly to a novel scraper blade to be applied to the draw-off roller and to special means for supporting and coacting with the blade, and generally speaking my invention resides in

certain improvements hereinafter described on the apparatus shown in Letters Patent of the United States heretofore granted to me, to-wit, Nos. 954,379 dated April 5, 1910 and 976,155 dated November 22, 1910.

I have preferably used printer's roller composition in the manufacture of the draw-off roller to which the scraper-blade is applied, and I have found that it is almost if not quite impossible to secure a draw-off 60 printer's roller composition roller or other yielding roller suitable for the purpose, having an exactly true surface throughout, but that, on the contrary, even with the exercise of great care in their production, the draw-off rollers have possessed undulations hardly perceptible to the eye, but which prevented the heretofore known scraper blades from removing all of the ink and solvent therefrom. Unless all of the ink and solvent are 65 removed from the draw-off roller during the cleansing operation, the rollers of the press do not become cleaned to the extent demanded. I have, therefore, in the present invention sought to provide a new construction of 70 scraper to be applied to the draw-off roller, and one which, regardless of the undulations present in the roller, will effectually remove all of the ink and solvent therefrom, thus 75 enabling the thorough cleansing of the rollers of the press.

The invention will be fully understood from the detailed description hereinafter presented, reference being had to the accompanying drawing, in which:

Figure 1 is a vertical longitudinal section through a portion of a printing press equipped with the features of my invention; Fig. 2 is a vertical transverse section through a rock-shaft or roller carrying the 95 scraper-blade of my invention and equipped with means for enabling the proper control and operation of the same, and Fig. 3 is a front elevation, partly broken away, of the roller shown in Fig. 2 and parts carried 100 thereby.

In the drawings, 10 designates the usual form-cylinder, 11 the impression-cylinder, 12 the ink-font, 14 composition form-inking rollers, 15 distributing rollers, 16 composition rollers in the train of said distributing rollers, and 17 an oscillatory roller of usual character for transferring the ink from the font 12 to one of said rollers 15, all of the rollers mentioned, as well as the form cylin- 110

der 10 and impression-cylinder 11, being of usual or any suitable construction and arrangement.

The features of my invention and which I apply as an addition to the press, are a draw-off roller 18 and a roller or rock-shaft 19 and the parts mounted on said shaft comprising a series of arms 20 carrying my flexible scraper-blade 21, a series of springs 22 independently acting against said arms 20 and a series of stop-arms 23 which are utilized at the proper time to hold the arms 20 and blade 21 in their inoperative position illustrated by dotted lines in Fig. 2, the solid lines in Fig. 2 representing the operative position of the scraper-blade 21 and its co-acting parts. The operative position of the scraper-blade 21 and draw-off roller 18 for cleaning the press is shown in Fig. 1.

The arms 20 are, each in itself, rigid throughout and each of said arms is formed with a ring or collar 24 closely encompassing but free on the roller or shaft 19. Each of the collars 24 has laterally projecting arms 25, 26 which serve to space them from substantially corresponding collars or bands 27 carrying and being integral with the stop arms 23, which alternate with the arms 20, as shown in Fig. 3. The arms 26 also serve as bearings for the lower portions of the springs 22 which are flexed around the shaft 19 and confined in part by said arms 26. The arms 20 in their upper portions are of goose-neck formation and provided with upwardly inclined heads 28 slotted laterally to create jaws for receiving the blade 21, and said arms 20 are provided at opposite sides with laterally extending pins 29 against which the upper ends of the springs 22 are flexed to enable them, when the arms 20 are otherwise released, to turn said arms and the scraper-blade 21 from their inoperative position, shown by dotted lines in Fig. 2, to their operative position illustrated by solid lines in Figs. 1 and 2, thereby setting the edge of the scraper-blade 21 against the draw-off roller 18.

The collars or bands 27 of the stop-arms 23 are feathered on the shaft 19 and also fastened thereto by screws 30, and said arms are made use of for turning the arms 20 from their operative to their inoperative position and maintaining them at such inoperative position. The springs 22 normally press against the pins 29 to turn the arms 20 forwardly toward the roller 18, and the arms 23 on the turning of the roller or shaft 19 to effect that result are caused to move against the pins 29 at the sides thereof opposite to those engaged by the springs 22, and thereby in opposition to the force of said springs turn the arms 20 upwardly to carry the blade 21 from the roller 18. Upon the rotation of the shaft or roller 19 downwardly in a direc-

tion toward the roller 18, the arms 23 turn from the pins 29 and allow the springs 22 to turn the collars 24 on the shaft 19 and move the arms 20 toward the roller 18. The collars 27 are formed with ears 31 through which pins 32 are passed with their ends projecting laterally beyond the collars, as shown in Fig. 3, and serving as bearings to confine the lower portions of the springs 22 against the shaft 19, the pins 32 thus cooperating with the arms 26 in maintaining the springs 22 in operative relation to the other features of the attachment.

The shaft or roller 19 may be turned downwardly in a direction toward the roller 18 manually or by any suitable means, and said shaft or roller 19 may be given a reverse movement to carry the stop arms 23 against the pins 29 of the arms 20 manually or by any suitable means.

The draw-off roller 18 is preferably mounted between a pair of pivoted arms 33 so that it may be free from the adjacent roller 15 when the press is in operation for printing purposes and it is not desired to clean the same. When, however, it is desired to clean the rollers of the press the roller 18 will be moved into engagement with the adjacent roller 15 so that the gear-wheels 34, 35 on said rollers may intermesh and the roller 18 be driven from the said roller 15 or the driving mechanism of the press. The roller 18 will preferably be of the printer's roller composition, but it may be of some other suitable substance having a yielding surface adapted to take the ink and solvent from the adjacent roller 15 during the cleaning of the rollers of the press.

When the rollers of the press are to be cleaned the ink-supplying roller 17 will be moved out of operation and the draw-off roller 18 moved against the adjacent roller 15, and thereupon the shaft or roller 19 will be turned downwardly and toward the said roller 18 so as to carry the stop-arms 23 from the pins 29 of the arms 20 and permit the springs 22 to turn the arms 20 toward said roller 18 and place the scraper 21 against said roller. Solvent of ink, such as kerosene, will be applied to one or more of the train of rollers to be cleaned and the press driven, with the result that the color and solvent will travel toward and be taken by the draw-off roller 18 from which the color and solvent will be constantly removed by the scraper blade 21, said color and solvent passing from said blade to a suitable trough 36 and thence to a suitable receiving receptacle 37. The constant removal of the color and solvent by the blade 21 enables the roller 18 to become a draw-off roller and the point of discharge for all of the ink and solvent from all of the train of rollers or connected inked surfaces. The rollers of the press will become very rapidly

cleaned with the use of my invention. In the illustration of my invention presented, the draw-off roller 18 is normally independent of the regular rollers of the press, but it may be permanently in or one of the train of rollers if desired and in that event the parts connected with the scraper-blade 21 would be the only movable parts of the attachment.

10 I very greatly prefer to clean the rollers while they are on the press, and my invention is particularly adapted for this purpose, but the features of my invention are also applicable for use in separate roller-washing machines to which the rollers removed from the press are delivered, and in such use of my invention the scraper-blade 21 may be applied directly to the printer's roller, but preferably it will be applied to a draw-off roller corresponding with the roller 18 engaged by the printer's roller.

In the patents hereinbefore referred to as having been granted to me is described a flexible scraper blade. The blade disclosed 25 in said patents is held at its shank portion throughout the entire length of the blade, and hence while flexible in a sense does not possess the flexibility of the present blade 21 which is held by the spaced apart arms 20 independently acted on by springs 22, whereby said arms 20 become independently yieldable and enable the blade 21 to bend across its width at points along its length at which irregularities of surface of the roller 35 18 may be presented to the blade. The efficiency of the cleaning attachment is very greatly enhanced by securing the blade 21 to independently yielding arms spring-pressed toward the roller to be cleaned. The irregularities of surface in the roller 18 are usually hardly perceptible to the eye and apparently non-preventable in the manufacture of the roller, and a scraper-blade to be efficient in the cleaning of the printers' rollers must be able to delicately and positively conform to the irregularities of surface presentation of the draw-off roller, to accomplish which result is the purpose of my present invention. The blade 21 is very flexible, 45 and it is held at spaced-apart points by independent spring yielding members, so that said blade along the line of its length may yield in sections to conform to the surface of the draw-off roller, or uniformly yield 50 bodily in a direction from the said roller should the irregularity of surface be caused by a straight line eccentricity of the composition on the stock or shaft of the roller, or yield to take changeable slanting line positions should the stock or shaft of the roller 55 not be concentric and parallel with the roller or should the said shaft be concentric with the

roller but be thrown out of true in its bearings by being worn more at one end than at the other end or by the bearing for one end 65 of said shaft being more worn than the bearing for the other end thereof.

I do not limit my invention to the details of form and construction presented.

What I claim as my invention and desire 70 to secure by Letters Patent, is:

1. For cleaning printers' rollers, a flexible scraper-blade to extend the length of a roller, a series of spaced-apart arms carrying said blade and independently movable, 75 at right angles to the longitudinal plane thereof, and a series of independent springs acting against said arms to yieldingly hold the blade against the roller and permit the blade to follow the surface of the roller. 80

2. For cleaning printers' rollers, a transfer roller for drawing off the foreign matter from the printer's roller, a flexible scraper-blade to be applied to said transfer or draw-off roller, a series of independent arms carrying said blade, and a series of independent springs yieldingly acting against said arms to hold the blade against the draw-off roller and permit said blade to yield and follow the surface of the roller. 85 90

3. For cleaning printers' rollers, a transfer roller for drawing off the foreign matter from the printer's roller, a flexible scraper-blade to be applied to said transfer or draw-off roller, a series of independent arms carrying said blade, springs yieldingly acting against said arms to hold the blade against the draw-off roller and permit said blade to yield and follow the surface of the roller, and means for positively moving said arms 100 in opposition to the force of said springs to carry said blade from the draw-off roller. 95

4. For cleaning printers' rollers, a transfer roller for drawing off the foreign matter from the printer's roller, a flexible scraper-blade to be applied to said transfer or draw-off roller, a rock-shaft, a series of independent spaced-apart arms freely mounted on said shaft and carrying said scraper-blade, a series of springs pressing against said 110 arms for yieldingly applying the blade to the roller, and a series of stops rigid with said shaft and alternating with said arms for moving said arms and said scraper-blade for moving said arms and said scraper-blade in opposition to the force of said springs to 115 an inoperative position.

Signed at New York city, in the county of New York and State of New York, this 20th day of June A. D. 1912.

SAMUEL CRUMP.
